TREILLAGE

Jacob G. Braun, Chicago, Ill.

Application October 28, 1952, Serial No. 22,012

Term of patent 14 years

(Cl. D35—2)

To all whom it may concern:

Be it known that I, Jacob G. Braun, a citizen of the United States, residing in the city of Chicago, in the county of Cook and State of Illinois, and having a post-office address at 609 South Pauline Street, Chicago, Illinois, have invented a new, original, and ornamental Design for a Treillage, of which the following is a specification, reference being had to the accompanying drawing, forming part thereof.

Fig. 1 is a front elevation of a treillage embodying my design.

The characteristic feature of my design resides in the particular configuration of the artistry within the illustrated framework.

The back of the treillage presents the same appearance as shown in Fig. 1.

I claim:

The ornamental design for a treillage, substantially as shown and described.
